UNITED STATES PATENT OFFICE.

GEORGE C. THOMAS, JR., OF ELIZABETH, NEW JERSEY, ASSIGNOR TO THE THOMAS & BETTS CO., OF ELIZABETH, NEW JERSEY, A CORPORATION OF NEW JERSEY.

CABLE CONNECTER.

Application filed January 22, 1924, Serial No. 687,780. Renewed June 6, 1927.

This invention relates to combination outlet boxes and cable connectors, and more particularly to connectors for use in anchoring electric cables or conduits to electric box fixtures, such as outlet boxes, switch boxes, cable boxes, and the like.

An object of the invention is to produce an improved cable connector of simple structure capable of being manufactured either by stamping the connector from sheet metal or by casting it and which entails a small quantity of material. Likewise it is an object to produce a cable connector which positively functions to securely fasten a cable to said box, as well as fasten it in standard round knock-out holes in boxes of present-day use; and one important feature resides in the fact that it simultaneously straddles the box wall opening and cable, and has means for simultaneously setting up an anchoring relation jointly with the cable and box.

Another object of the invention is to produce a connector from a flat stamping which includes box hole anchorage means into which is received a box hole edge to anchor the connector against longitudinal displacement, and cable clamp means is carried on the connector acting directly on the cable to grip the cable between an exposed box hole edge and the connector and to simultaneously render effective the said anchorage means.

A further object of the invention is to produce a cable connector, including box hole anchorage or abutment means, of suitable size to fit into a box hole and so formed as to directly expose a portion of the box hole edge to a cable received into the box hole, and to provide operating means, such as a screw, inside the box to bear or clamp directly toward or against the cable, the effect of which is to simultaneously render effective the anchorage means and grip the cable between the exposed box hole edge and screw, the latter being inside the box.

The accompanying drawing illustrates a preferred form of the invention, the construction of which may be varied or modified without departing from the scope and principle of my invention.

Figure 1 illustrates a top view of an outlet box showing a cable joined thereto; and the lower half of the view illustrates a connector in position in the box before the

cable is inserted. Figure 2 shows an end projection of Figure 1.

Figure 3 illustrates a sectional view taken on the line 3—3 of Figures 1 and 2; and Figure 4 illustrates a sectional view taken on the line 4—4 of Figure 1.

Figure 5 shows a cluster view of the connector.

Figures 6 and 7 show a modified form of connector assembled in the box and removed therefrom.

Figures 8 and 9 illustrate another modified connector assembled in the box and removed therefrom.

Referring now more particularly to the drawings for a more detailed description of the invention, there is shown a cable connector of such design, arrangement and construction as may be cast, or the connector may be struck or stamped from sheet metal by a punch press operation. The connector essentially comprises a single piece structure of generally U-shaped design, there being parallel plates or legs depending or bent down right-angular from a web or body 8. The plate or leg integral with the body 8 is provided with an opening either round, or as in this instance, it may be U-shaped as shown at 9, the said hole or opening 9 being formed in an abutment plate 10 which integrally joins a narrow neck of stock 11 on the connector web body 8. The structure of the neck is such that a box hole edge receptacle groove or notch 12 is formed on each side of the neck in the web adjacent the abutment plate or leg 10. The inner face of the abutment plate 10 forms one wall of the connector anchorage notches 12, while the other notch wall is defined by the edges of the body 8. The abutment plate 10 possesses sufficient spread or area as will afford a positive closure for box knock-out holes thus leaving no cracks or openings in the sealed electric box.

The other end of the body or web 8 carries a bent down or depending part 14, and this part is spaced in parallel relation from the abutment plate 10, and stands outwardly from the box wall as shown in the assembled view Figure 3. This depending leg or plate 14 is made with a swedged out rim or collar which provides a bushing 15; and the bushing is made with a hole 16 through which the cable wires W pass, and the wires are pro-

seated position against the box hole edge and thus renders the anchorage means effective to anchor the connector in the box hole against longitudinal displacement.

5 In accordance with the principles of this invention, the single clamping or operating means, such as the screw 18 or 28, is carried with the connector member, and may to advantage be placed inside the box for old 10 house work or on the outside of the box for new house work by which to force or grip the cable against the exposed box hole edge. Heretofore it was necessary to screw fasten the connector to the box, an obvious disadvantage because standard type outlet boxes 15 now in use are not manufactured with a screw hole or holes by which to anchor the connector to the box wall.

My invention affords a simple type of 20 cable connector with only one operating part, the screw, which may conveniently be placed inside the box for old house work and outside the box for new house work. Thus the connector is universal in its several adaptations as clearly shown for example in Figure 9, because that connector is simply reversible to place the screw 28 in or out of the box as building requirements may demand.

What I claim is:

30 1. Cable and box connecting means comprising, a box having a cable and connector receiving hole, a substantially flat plate connector of such size as will fit through the box hole and formed to directly expose a portion of said box hole edge to a cable, box 35 hole edge anchorage means included on the connector into which seats the box hole edge to fix the connector in the box hole, and means rotatably mounted on the connector bearing on the cable to grip it between the connector and exposed box hole edge and to simultaneously force the anchorage means 40 into fixed relation with the box hole edge.

45 2. Cable and box connecting means comprising, a box having a cable and connector receiving hole, a substantially flat plate connector of such size as will fit through the box hole and formed to directly expose a portion of said box hole edge to a cable, box hole 50 edge anchorage means included on the connector into which seats the box hole edge to fix the connector in a box hole, and a screw threaded through the connector toward the cable to grip it between the exposed box hole edge and screw and to force the anchorage means against the box hole edge.

55 3. Cable and box connecting means comprising, a box having a cable and connector receiving hole, a substantially flat plate connector of such size as will fit through the box hole and formed to directly expose a portion of said box hole edge to a cable, box hole 60 edge anchorage means included on the connector into which seats the box hole edge to fix the connector against longitudinal dis-

placement, a screw threaded through the connector toward the cable to grip it against the exposed box hole edge and to force the anchorage means against the box hole edge, and a downturned end included on the plate 70 inside the box against which stops the end of the cable.

4. A cable box and connecting means as defined in claim 3 wherein the screw is placed between the box hole anchorage means 75 and downturned end.

5. A cable and box connecting means comprising, a box having a hole, a U-shaped connector placed in the box hole and including box hole edge anchorage means made in the 80 base of the U with the hole edge seated into the anchorage means, one leg of the U being outside the box wall and including an opening through which a cable passes into and through the box hole and said outside leg 85 forming a plate which closes the box hole around the cable, the other leg of the U being inside the box and including a wire bushing, and a screw threaded through the base of the U-shaped connector and directed 90 toward the cable to force it against the box hole edge and to also seat the connector anchorage means against the box hole edge.

6. A connector comprising, a substantially flat plate including box hole edge anchorage means, and a rotatable member mounted thereon including means to force said member against a cable and to render effective the anchorage means.

7. A connector comprising, a stamped 100 plate connector including box hole edge anchorage means, and a screw threaded through the connector to grip a cable against an exposed box hole edge.

8. A connector comprising, a substantially flat plate including box hole edge anchorage means, a screw threaded through the connector, and said screw being placed adjacent the anchorage means and projecting through the connector substantially parallel to the 105 plane of the box hole edge anchorage means.

9. A connector comprising, a substantially flat plate including notched box hole edge receiving means, and a screw threaded through the connector adjacent the notched 110 box hole edge receiving means to grip a cable against an exposed box hole edge.

10. A connector comprising, a substantially flat plate being provided with two spaced box hole edge receiving notches in alignment formed in opposite edges of the plate, and a screw threaded through the plate adjacent the notches to grip a cable against an exposed box hole edge.

11. A connector comprising, a substantially flat plate including box hole edge anchorage means, said plate having one end bent at right angles with an opening there in for a cable to pass through, and a screw 125 threaded through the plate directed toward

the cable to grip it against an exposed box hole edge.

12. A connector as defined in claim 11 wherein the anchorage means constitutes a pair of box hole edge notches made in the edges of the plate.

13. A connector comprising, a substantially flat plate including box hole edge anchorage means and the plate being turned down at each end to form a U-shaped part, the legs of the U having openings therethrough, and a screw threaded through the plate between and substantially parallel to the legs.

14. A connector comprising, a substantially flat plate including box hole edge receiving notches, a screw threaded through the plate on one end thereof adjacent the notches, and the other end of the plate bent at right angles with opening therethrough which places the notches between the screw and bent end.

15. Cable and box connecting means comprising, a box having a cable and connector receiving hole, a connector member of such size as will fit through the box hole and formed to directly expose a portion of said

box hole edge to a cable, box hole edge anchorage means included on the connector into which seats the box hole edge to anchor the connector in the box hole, and operating means rotatably mounted on and carried with the connector inside the box and bearing against and directly toward the cable to grip it between the connector and exposed box hole edge and to simultaneously seat the anchorage means against the box hole edge.

16. A connector comprising a member of suitable size to fit into a box hole and formed to expose a portion of the box hole edge directly to a cable received therewith and including box hole edge anchorage means, a portion formed on the connector member proximate the anchorage means to project through a box hole to the inside of a box, and operating means carried with the portion inside a box and bearing against and directly toward the cable to grip it between the operating means and exposed box hole edge and to engage the anchorage means against the box hole edge.

In testimony whereof I affix my signature.
